CLAIM

The ornamental design for a shoe, as shown and described.

DESCRIPTION

FIG. 1 is a left side elevational view of an ornamental design for a shoe;

FIG. 2 is a rear elevational view of the shoe of FIG. 1; and, FIG. 3 is a right side elevational view of the shoe of FIG. 1. The dash-dash-dash lines depicting the upper and lower boundaries of the shoe, and the differently weighted dash-dash-dash lines therebetween, are included for the purpose of illustrating portions of the shoe that form no part of the claimed design.
